(57) **CLAIM**

The ornamental design for a convertible gun case, as shown and described.

DESCRIPTION

FIG. 1 is a top perspective view showing my new design; FIG. 2 is a top perspective thereof; FIG. 3 is a top view thereof; FIG. 4 is a front view thereof; FIG. 5 is a left side view thereof; FIG. 6 is a right side view thereof; FIG. 7 is a bottom view thereof; FIG. 8 is a rear view thereof; FIG. 9 is a perspective view in a first convertible position thereof; FIG. 10 is a perspective view in a second convertible position thereof; FIG. 11 is another perspective view in the second convertible position thereof; and, FIG. 12 is a top perspective view thereof. The broken lines of FIG. 12 show environment of the article, including stitching, straps, and a handle, that form no part of the claimed design.
